UNITED STATES PATENT OFFICE

WARREN S. WATTS, OF LOUISVILLE, KENTUCKY, ASSIGNOR TO ARLETTE, INC., OF LOUISVILLE, KENTUCKY, A CORPORATION OF DELAWARE

HAIR-WAVING WRAPPER

Application filed March 21, 1929. Serial No. 348,867.

The invention relates to a device used for encasing a lock of hair which has been rolled about a curling iron, and is employed for producing what is known as a "permanent" wave. The invention resides particularly in the structural details of the encasing device.

Heretofore, two applications for Letters Patent have been made in the name of the present applicant, these being, Serial No. 324,504, entitled Hair waving wrapper, and filed December 7, 1928, and Serial No. 327,808, entitled Hair waving wrapper, and filed December 22, 1928.

The present invention contemplates an improvement over the previously filed above referred to applications.

This improvement has to do with improved structural arrangements whereby the hair curling liquid which may have a tendency to collect in the corners of pocket holding the pad is properly discharged, and the undesirable retention or excess of moisture in such corners avoided. This result is accomplished by a modification of the form of wrapper illustrated in the applications for patent above referred to, and the structural reconstruction provides the addition of a slit or orifice or opening adjacent each lower corner of the pad holding pocket. Such opening or aperture permits of the hair curling fluid in the corners of the pad freely escaping from the envelope. Thus, the entire quantity of hair curling liquid with which the pad is saturated is permitted to affect the hair, this being most desirable when measured volumes of hair curling liquid are employed.

The objects of the invention include, of course, the production of an article readily manufactured, one which may be produced at a low cost, and one having a pleasing appearance. In addition thereto, the objects of the invention include the provision of structural features which will permit of the rapid, ready, and complete discharge from the absorbent pad in the device of all of the hair curling fluid with which it is charged. Such discharge will be evenly distributed over the lock of wound hair by the present arrangement. These last mentioned objects are in addition to the objects recited in applicant's

previously filed applications for Letters Patent, herein above referred to, the present structural modifications being in a nature of an improvement over a heretofore new and unique hair curling sachets invented by the applicant.

The objects of the invention herein above referred to and such other objects as may hereafter appear, are obtained by the novel construction, arrangement, and combination of the several elements forming the one embodiment of the invention herein described and fully illustrated.

Only one form of the invention is disclosed in the accompanying single sheet of drawing hereby made a part of this application for Letters Patent but such invention is applicable to a number of different sachets.

In the drawing

Figure 1 is a plan view of a blank used for forming the hair waving casing;

Figure 2 is a fragmentary view of the end portion of the blank shown in Figure 1 partially assembled and illustrating the method of forming the pocket therein;

Figure 3 is a plan view of the metallic foil sheet used in association with the casing;

Figure 4 is a plan view of the textile pad which is adapted to be associated with the casing and foil;

Figure 5 is a plan view of an assembled sachet; and

Figure 6 is a transverse section of the completed sachet shown in Figure 5 and is taken on the line 5—5 thereof, looking in the direction of the arrows.

Like reference characters are used to designate similar parts in the drawing and in the description of the invention to be hereinafter given.

Reference should be had first to Figure 1. There is shown in said figure a blank which may be of parchment or other paper, or of other suitable material, in sheet form, and adapted for the purposes of manufacturing hair sachets.

The blank illustrated in Figure 1 comprises a main portion 10, the body of which is of greater area than of any of the remaining section of such blank. Said portion 10 and

the adjacent portion of the blank which forms a part of the inside of the finished sachet are separated by a fold in the assembled device, the fold line being represented in Figure 1 by dotted line 11. Such inside portion of the sachet is designated by the ordinal 12. One face of section 10 forms the external or exposed back portion of the sachet.

10 Integral with section 10 is an extension 13 which comprises, in the assembled device, one layer or lamination of an envelope or pocket formed by the articulation of the material disposed at the other end of said blank.

15 From said opposite side of the body 10 and appended to section 12 and separated therefrom at one side by a slit or by a V-shaped incision 14 is the portion of the blank employed for the formation of a pocket to 20 receive a pad. The pocket forming section includes a projecting rectangular section 15 and which forms the back of the pocket. When assembled, this section is folded upon the dotted line 16.

25 Between sections 12 and 15 is a windowed section 17, the opening therein being designated 18. Such window is of any suitable size, but should not be so large that a pad to be inserted into the pocket may accidentally 30 slip therefrom. The proportions of the window 18 to section 17 shown in the drawing are generally satisfactory. At the ends of the fold line 16 are two slits 16a extending into the envelope to provide openings therein 35 for the escape of moisture. In place of these apertures other types of openings could be employed and serve with equal facility.

At each end of the section 17 and separated therefrom by folds represented by dotted lines 40 19 and 20, are lateral extensions 21. To form a pocket, designated as an entirety 22, section 12 is folded forwardly on the fold line 11 and over the member 10 after which the ends 21 are folded upon the lines 19 and 20 to lap 45 over and upon the back of section 13. Ends 21 are adhesively secured to section 13. Then member 15 is folded on line 16 and adhesively applied over ends 21 and the remaining exposed portion of member 13. Thus the 50 pocket 22 is formed, there being an opening 18 in the one layer front 17 of said pocket, and two openings or slits 16a in the lower corners thereof. A laminated back comprising sections 13, 21, and 15 is thus also provided.

The manner of folding the blank shown in Figure 1 whereby to obtain pocket 22 is best illustrated in Figure 2. This assembly is made only with the foil sheet hereinafter described in its proper relation to the casing sections.

Figure 3 illustrates a sheet of foil material 30 having an extension portion 31. These two sections are integral. For convenience of description, an imaginary divisional

line 32 is shown. The portion 30 corresponds with section 10 of the casing blank and in the assembled article extends approximately to the right-hand edge thereof as is shown in Figure 1, but does not extend quite to the 70 left-hand edge thereof. Normally the foil reaches to approximately one half inch from the left-hand edge of said section 10. It is not desirable to have metal or metallic foil come into direct contact with the human scalp, 75 hence there is a small amount of clearance at the left-hand end of section 10 and over which the foil sheet does not extend.

The foil which is employed may be plain foil or it may be a backed foil. When backed foil is used, it may have a paper backing. Preferably a backing is employed, for this diminishes the amount of metal required because thinner metal may be used and it reduces the danger of damage to the foil sheet 85 without disturbing the other characteristics which make foil desirable for use in hair sachets.

In assembling the device, the foil extension 31 is inserted into pocket 22. When a backed foil is used, the metal surface is uppermost. When there is a backing upon the foil, such backing will come directly in contact with the inner face of portion 10 of the casing, and the backing on section 31 of the foil will come into contact with the inner face of portion 13 of the pocket. When so inserted and disposed, the casing is assembled as previously directed.

Reference will now be had to Figure 4. 100 This shows a pad of absorbent material upon which a solution used for softening and/or curling the hair is disposed. Such solution may be of any of the usual ingredients now employed or any which may be discovered 105 in the future. The pad generally comprises a highly absorbent material like felt enclosed within a harder material similar to that employed for bandages or surgical gauze.

110 While the core or interior portion of the pad is generally a section of soft felt, any other absorbent material may be employed without departing from the spirit of the invention. The entire pad is designated 40, and it is adapted to be inserted into and is inserted into pocket 22 in assembling the complete device. The back of the pad 40 rests upon the front surface of the section 32 of the foil sheet. The front portion of such pad 40 is almost wholly exposed through the window 18.

115 For holding the pad 40 within the pocket in envelope 22 and for holding the foil extension 31 also therein, a single stitching or a staple 41, as shown in Figure 5, is all that is necessary. The foil is thus held against displacement by the structure of the casing, although subject to relatively slight move- 120 125

ments within the casing until the staple 41 is inserted.

Preliminary to use, the pad 40 may be charged in any of the conventional manners. It may be dipped into a solution which is to be used thereon, or such solution may be made to impregnate the pad by the use of a pipette, a measuring device, or any other selected instrumentality whereby such solution is transferred from a container to the pad 40. As it is now recognized that a definite quantity of a solution of any fixed characteristic should be employed for each curl, it is quite usual to pour a measured quantity of the selected solution upon a pad 40.

In the finished sachet, when in flat form, there is exposed a section of foil 30 several inches in breadth and approximately one inch in length and having the casing at the back side only thereof. This right-hand end of the sachet, Figure 5, is twisted or crimped, there being sufficient body in the sheet of foil to insure that such sachet, when so crimped, will permanently be held about the lock of curled hair until the proper time for its removal after the heat of the hair curling machine has been applied thereto.

The sachet, after the pad 40 therein has been moistened, is wrapped about a lock of hair which is twisted upon a suitable curling rod or iron. That part of the sachet comprising two thicknesses of paper without an intermediate foil section is disposed adjacent to the scalp. The pad portion 40, of course, is the first portion to be wrapped about the hair. To allow free escape of liquid therefrom when so wrapped, the slits 16a are helpful.

When the entire sachet is wrapped around the curled lock of hair upon the curling rod or iron about which the hair is twisted, the hair and iron are covered.

Such a sachet as is here illustrated provides an impervious back section through which the moisture from the pad 40, even when converted into steam, cannot readily escape to the outside atmosphere. Through the front, freedom of discharge is had. It thus insures the full benefit of the moisture contained in the pad for steaming and curling the hair and the whole effect of the chemical ingredients employed thereon for the treatment or softening of the hair.

As presented, the device comprises three sections, each adapted to be produced separately in a machine, there being a relatively simple assembly therebetween. One fastening number is all that is required to maintain the three parts in their assembled relation, thus, the cost of production and assembly is very much reduced.

I claim:

1. A sachet for hair waving comprising a pad holding section having a window on one

side thereof, and a moisture releasing ancillary opening associated therewith.

2. A sachet for hair waving comprising a body of material having an open face, and a plurality of slits in said body to aid in the escape of moisture from said body. 70

3. A sachet for hair waving comprising sheet material providing a casing having a window, and additional openings in said sheet cooperating with said window to allow the escape of moisture. 75

4. A sachet for hair waving comprising sheet material cut and folded to provide a pad holding pocket having a window therein, and ancillary moisture releasing openings removed from said window. 80

5. An open faced sachet for hair waving comprising a casing for an inserted pad, said casing having at its corners openings to allow the escape of moisture from said pad. 85

6. A sachet for hair waving comprising a sheet of material folded to form a pocket to receive an absorbent pad, there being a window in said pocket exposing the central portion of a pad and associated smaller openings at the margin of said pocket to allow the escape of moisture collected on the edge of said pad. 90

7. A sachet for hair waving comprising a pocket having an open window, said pocket having corner apertures to assist in the escape of moisture therefrom. 95

8. A sachet for hair waving comprising a two layer flat casing, one of said layers having an aperture therein forming an open sided pocket to receive a pad adapted to absorb a hair waving solution, there being in the corner of said pocket slits to allow the escape of moisture from said pad. 100

9. A sachet for hair waving comprising sheet material folded to provide a two sided casing within which a pad may be inserted, one of said sides having an opening adapted to allow moisture to escape from the body of such pad, there being an additional aperture between said layers to augment the discharge of such moisture. 105

10. A blank for forming a sachet for hair waving and comprising a sheet adapted to be folded upon itself to provide a casing, said blank having a plurality of extensions cooperating one with another to form an open sided pocket, there being slits between sections thereof to provide ancillary openings in said casing. 115

11. A sachet for hair waving comprising sheet material cut and folded to form a body section of two layers and having extensions providing a pocket to receive an absorbent pad, one of the extensions having a main aperture therein and being divided from an adjacent section by a slit forming a secondary aperture therein. 125

12. A sachet for hair waving comprising contiguous sheets of material to provide a 130

pad casing, one sheet of said casing having a window therein for exposing the face of the pad and an extension therefrom, the division between said extension and sheet having an aperture for releasing moisture collected on the edge of said pad.
